UNITED STATES PATENT OFFICE

WILLIAM E. WOODARD, OF FOREST HILLS, NEW YORK

LOCOMOTIVE SNOWPLOW

Application filed March 14, 1927. Serial No. 175,388.

This invention relates to locomotive snow plows and the nature, objects and advantages will be best appreciated from the following:

A locomotive cannot ordinarily function as 5 its own snow plow. However, by providing a locomotive with a bumper and pilot of a design and construction such that snow plates may be detachably associated therewith and be supported thereby in a manner such 10 that the combined structure can function as a snow plow, any locomotive may be readily put in condition to function as its own snow plow. It is the primary object of my invention to make this possible.

15 How the foregoing, together with such other objects as may hereinafter appear or are incident to my invention are obtained is illustrated in the accompanying drawings wherein

20 Fig. 1 is a plan view of one embodiment of my invention showing the plow attached to a locomotive.

Fig. 2 is a front elevation of Fig. 1.

Fig. 3 is a section taken on the line 3—3 25 of Fig. 2 and

Fig. 4 is a vertical section taken on the line 4—4 of Fig. 2.

Referring now to the drawings the reference letter A indicates the forward end of a 30 locomotive to which is secured the bumper B having pilot C. The bumper comprises the beam 5 having wings 6—6 extending outwardly and rearwardly from the beam. The V-shaped pilot C is secured to the front of the

35 bumper beam and comprises two triangular upper wing portions 7—7 and base portion 8.

The upper wing portions are secured to the bumper beam 5 by means of bolts 9 and the base 8 is secured to the beam 5 by means of 40 brackets and straps (not shown) which extend downward from the beam 5 and are appropriately secured to the base 8, thus forming a strong well supported pilot.

The coupler pocket casting 10 fills the 45 space between the wings 7—7 of the pilot and is secured to the bumper beam 5 by means of bolts 15. The coupler 16 is pivoted in this casting.

It will be seen that this bumper and pilot 50 arrangement forms a V-shaped structure

with the wings 6—6 of the bumper beam 5 forming a continuation of the general V-shape of the pilot.

Located in front of the pilot C and bumper B are two flat snow plates 11—11 having 55 wings 11^a—11^a projecting beyond the sides of the pilot. The main portion of these plates is marginally secured to the pilot by means of bolts 12 where the rear of the pilot is readily accessible and by means of bolts 60 13 where certain portions of the pilot are difficult of access from the rear. Bolts 12 are of ordinary form, but the bolts 13 are T-headed (see Fig. 4) and can be inserted from the front and then turned so that the T-head 65 fits between upstanding lugs 14 which prevent the bolt from turning when the T-head is engaged thereby.

The pilot is provided with appropriate 70 openings to permit of the insertion of the bolts 12 and 13 which marginally secure the snow plates 11 thereto and the wings 6—6 of the bumper beam also have appropriate openings for a like purpose. These snow plates 75 are thus detachably secured to the pilot and bumper and can be quickly and easily applied and removed.

The wings 11^a—11^a of the snow plates are 80 secured to the wings 6—6 of the bumper beam 5 and the lower portion thereof is cut away in order that the plow may relieve itself of the snow more readily at the lower part thereof and it will be seen by inspection of Figs. 1 and 2 that the rails will be cleared.

The plates 11 do not meet at the apex of the 85 V as the base 8 of the pilot is solid at this point and the coupler pocket casting 10 and coupler 16 fill the apex above the base portion 90 of the pilot. The plates 11 are cut to fit around this coupler pocket casting.

It will be seen that the pilot forms a 95 strong support for the centre of the plow, the coupler casting 10, coupler 16 and apex of the base 8 actually forming that part of the plow where the thrusts are greatest, i. e., the apex. The main portion of the plates 11 lies against and is supported and backed by the rest of the pilot throughout their vertical height and the wings 11^a of the plates forming the plow 100

are secured to and supported and backed by the wings 6—6 of the bumper beam 5.

The whole structure forms a V-shaped front of practically uninterrupted surface and the coordination of parts is such that the structure is one well calculated to meet the thrust conditions met in service.

I claim:

1. The combination with a locomotive of a bumper and V-shaped pilot, said bumper having rearwardly extending wings forming a continuation of the V and flat snow plates secured to the pilot, said plates also having wings which are secured to the wings of the bumper.

2. The combination with a locomotive of a bumper and V-shaped pilot, flat snow plates marginally secured to the pilot at three sides and extending beyond the pilot at the fourth side and wings on said bumper forming a support for that part of the plates which project beyond the pilot.

3. The combination with a locomotive of a bumper and V-shaped pilot, flat snow plates secured to the pilot and projecting laterally therebeyond and means on said bumper forming a support for the said projecting portions of the plates.

4. The combination with a locomotive of a bumper and V-shaped pilot, said bumper having rearwardly extending wings forming a continuation of the V and flat snow plates secured to the pilot, said plates also having wings which are secured to the wings of the bumper, the lower portion of the wings of said plates being cut away.

5. The combination with a locomotive of a bumper having a beam with a flat central portion and angular wings projecting rearwardly from each side of the flat central portion, a triangular pilot member having one side secured to the flat central portion of the bumper and flat snow plates secured to said pilot, said plates having wing portions which are secured to the wings of the bumper.

In testimony whereof, I have hereunto signed my name.

WILLIAM E. WOODARD.
